[57] CLAIM

The ornamental design for a cap and package for package of chewing gum, as shown and described.

DESCRIPTION

FIG. 1 is an exploded perspective view of the cap and package for package of chewing gum with the top portion dispensing elements in an opened position showing my new design;

FIG. 2 is a front side elevational view thereof with the top portion in an unopened position, the back side is a mirror image of that shown;

FIG. 3 is a side elevational view thereof, the other side is a mirror image of that shown;

FIG. 4 is a bottom view thereof; and,

FIG. 5 is a top plan view thereof.
